MACHINE FOR USE IN MAKING PREWELT SHOES

Adrien L. Jalbert, Haverhill, Mass., assignor to
United Shoe Machinery Corporation, Flemington, N. J., a corporation of New Jersey

Application June 16, 1941, Serial No. 398,291

15 Claims. (Cl. 12—97)

This invention relates to machines for use in the manufacture of shoes and is illustrated herein with reference to prewelt shoes.

An object of the invention is to provide an improved machine for use in the manufacture of prewelt shoes.

In the manufacture of prewelt shoes, as herein illustrated, a single sole is provided having a peripheral channel in its edge face and adapted to be assembled off a last with a prewelt shoe upper. The welt on the upper is first straightened by utilizing cooperating rolls to cause it to assume the substantially flat position relatively to the upper that it will assume in a shoe, the cooperating rolls being also arranged simultaneously to conform the upper to the shape of said rolls around the forward portion of the upper but not around its rear or heel portion. In assembling the sole and the prewelt shoe upper off a last, the sole is bent or arched to shorten it lengthwise and it is introduced while in this bent condition into the opening at the bottom of the upper until the outer side of the channel in the sole engages the attaching face of the straightened welt, thereby positioning the welt and upper with reference to the sole. The sole is then released from its bent condition to permit it to spring back through resiliency to its normal substantially straight position, thereby causing it to assume its full length which, in turn, causes the sole to engage the upper and welt around the entire lower margin of the upper and which also positions or draws the upper and welt into or partially into the channel in the sole, the shoe parts having first been treated with cement so that they will be in condition to become cement attached when they have been properly positioned with respect to each other.

The upper and welt may then be tucked into the channel in the sole for the full depth thereof and the cement allowed to set to cause the sole to become cement attached to the upper and welt around the entire shoe, after which the sole may be permanently attached to the shoe by outseam stitches passing through the welt and sole, the stitches being spaced outwardly from the channel in the sole.

In accordance with one of its features, the illustrated invention provides an improved machine particularly adapted for use in practicing the method outlined above, the machine having means for bending the welt of a prewelt shoe upper away from the adjacent upper and into a predetermined angular relation thereto in order to cause the welt to assume the substantially

flat position it will assume in a shoe, the machine also having means for simultaneously shaping or conforming the upper adjacent to the welt into the shape desired in the finished shoe. As illustrated, the welt positioning and upper conforming means comprises a pair of cooperating rolls, one roll acting to support the shoe upper and being shaped in accordance with the shape of the upper desired in the shoe. This supporting roll is also provided with an inclined surface or flange arranged to be engaged by the welt to position it at a predetermined angular relation to the adjacent upper. The other cooperating roll is for pressing the shoe upper against the supporting roll to feed the upper and simultaneously to conform it to the shape of the supporting roll and also to force the welt against said inclined surface or flange to position the welt at the desired angle to the upper.

20 A prewelt shoe upper of the type referred to usually has a counter stiffener or fiber or similar material incorporated in its heel portion between the lining and upper and, accordingly, it is important, when operating upon the heel portion of the upper, that the cooperating rolls of the machine should not conform or shape such portion since this might crush or otherwise damage the upper or the counter stiffener therein. The rolls should, however, continue to operate upon the welt and adjacent portion of the upper around said heel portion in order to locate the welt in the desired angular position.

To this end and in accordance with another feature of the invention, the second or cooperating roll has a portion thereof which is separable or movable axially from another portion thereof while the rolls are rotating and operating upon the upper so that this separable portion may be separated from its other portion to move it out of engagement with the upper and thereby prevent said movable or separable portion from operating upon the upper. As herein illustrated, the separable portion of the cooperating roll is adapted to engage the upper at a considerable distance above the welt while said other portion of the roll engages the upper adjacent to the welt. When the movable portion is separated and moved axially from said other portion, this latter portion may continue with the supporting roll to operate in straightening the welt and shaping the upper adjacent thereto around the heel portion of the upper without conforming or shaping the counter stiffener incorporated in said heel portion.

With the above and other objects and features

in view, the invention will now be described in connection with the accompanying drawings and will thereafter be pointed out in the claims.

In the drawings,

Fig. 1 is a side elevation of a machine for operating upon shoe uppers, the machine being shown operating upon a prewelt shoe upper with portions of the machine and upper being shown in section;

Fig. 2 is a view similar to Fig. 1 but with the parts shown in a different position operating upon the heel portion of the upper;

Fig. 3 is a side elevation, partly broken away and in section, of a prewelt shoe upper;

Fig. 4 illustrates a sole comprising inner, outer and intermediate layers with the layers arranged so that a channel is provided around the edge face of the sole;

Fig. 5 shows the upper after it has been shaped and the welt thereon has been straightened, the sole of Fig. 4 being also shown in position for assembly off a last with the upper;

Fig. 6 shows the upper and sole after they have been assembled;

Fig. 7 is an enlarged sectional view of the toe portion of the shoe, illustrating the completion of the assembling operation.

Fig. 8 is a view similar to Fig. 7 showing the sole attached to the welt by stitches; and

Fig. 9 is a sectional view showing the upper being conformed or shaped by an expansible last in the shoe.

The illustrated machine comprises a base 10 arranged to be secured by screws to a bench or other support and having at its forward and rear ends, respectively, upstanding portions 12 and 14 in which is journaled a horizontal shaft 16 arranged to be rotated by a pulley 18 fastened by a set screw to the shaft, the pulley being driven by a belt 20 connected to any usual source of power. The shaft 16 is prevented from axial movement in the base by a collar 22 pinned to the shaft and engaging the forward surface of the portion 12. The shaft extends forwardly of the portion 12 and has secured to its forward end a roll 24 for supporting a shoe upper to be operated upon off a last such, for example, as the prewelt shoe upper A of Fig. 3, the roll, as illustrated, being adapted to extend inside the upper to support it from its inner side and being curved or rounded at its forward portion in accordance with the shape desired in the lower portion of the upper around the forepart thereof but forwardly of its rear or heel portion where a counter stiffener is usually located.

The supporting roll 24 has a groove 26 rearwardly of its rounded portion adapted to receive the lower edge of the upper and, in the case of a prewelt shoe upper as herein illustrated, to receive also the inner edge of a welt W attached to the upper. The roll then increases in diameter to provide an annular flange 28 having a rearwardly inclined surface 30 thereon adapted to be engaged by the welt W to position the welt in a predetermined angular relation to the adjacent portion of the upper, this angular position being such that, after the upper has been operated upon, the tendency of the welt to react and return to its original position will have been overcome sufficiently to cause the welt to assume the substantially straight or flat position which, it will assume in a finished shoe.

The upstanding portion 14 at the rear of the base 10 is bifurcated to provide ears between which is pivotally mounted on a transverse pin

32 a bracket 34 which extends upwardly and forwardly and, at its forward end opposite the portion 12, projects downwardly to provide a portion 36 which, together with the rear portion of the bracket, provides bearings for another horizontal shaft 38 parallel to the lower shaft 16. Inwardly of its bearing 14 the shaft 16 carries a gear 40 which meshes with a similar gear 42 secured to the upper shaft 38 so that, when the shaft 16 is rotated by the pulley 18, the shaft 38 will be rotated at an equal speed but in an opposite direction. The shaft 38 is retained against axial movement in the bracket by a collar 44 secured to the shaft by a set screw and engaging the rear surface of the forward bearing 36.

The shaft 38 has a reduced portion 46 at its forward end and mounted on this reduced portion above the supporting roll 24 is another roll 48 (Fig. 1) arranged to cooperate with the supporting roll in operating upon the shoe upper. The cooperating roll 48 is made up of two separate portions or sections, an inner or rear portion 50 which is fixed to the reduced shaft 46 by any usual means so that it rotates therewith, and a forward portion 52 which, as herein illustrated, is loose on the shaft 46. As illustrated in Figs. 1 and 2, the rear portion 50 of the roll 48 is positioned opposite the supporting roll 24 and has inclined surfaces thereon which converge to a thin edge and are so positioned and shaped that the portion 50 is complementary to the rear or grooved portion of the supporting roll.

The forward portion 52 of the roll 48 conforms substantially in shape to the corresponding portion of the roll 24, the portion 52, however, terminating in a cylinder in which is formed an annular groove 54. The fixed portion 50 has rigidly secured therein a plurality of horizontal rods 56 which extend forwardly and pass slidably through holes in the portion 52 so that this latter portion is always connected to the fixed portion 50 and is caused to rotate with it whenever the shaft 38 is rotated. Since the portion 52 is loose or slidable on the shaft 46, it can be moved axially thereon toward and away from the fixed portion 50 while the rolls are rotating. The portion 52 of the cooperating roll, therefore, is separable from the fixed portion 50 by axial movement while the rolls are rotating and are operating upon the work. During its separation the portion 52 will, of course, continue to rotate by reason of the horizontal rods 56.

The purpose of this construction is to permit the separable portion 52 of the roll 48 to be moved away from the fixed portion 50 and out of engagement with the shoe upper when operating upon its heel portion which contains the counter stiffener, thereby preventing the separable portion from operating upon said heel portion or the counter stiffener. As stated, the movement of the separable portion 52 toward and away from the fixed portion 50 must take place while the rolls are rotating and operating upon the heel portion of the upper so that the welt and the lower portion of the upper will be positioned and shaped as desired around the entire upper. Since the uppers will vary in size and shape, the separation of the two portions 50, 52 of the roll 48 must be capable of being accomplished at the will of the operator so that when a particular upper has been fed by the rolls into a position where its heel portion is about to pass between the rolls, the operator can move the separable portion 52 axially away from the fixed portion 50. The means for moving the separable portion

52 axially toward and away from the portion 50 while the rolls are rotating comprises a horizontal slide 60 arranged for movement back and forth in a plane parallel to the axis of the co-operating roll 48. The slide 60 is mounted on a supporting plate 62 secured by screws 64 (Fig. 1) to the bracket 34, the plate extending forwardly of the bracket. A guideway for the slide 60 is provided on the plate 62 by blocks 66, 68 secured respectively to the front and rear portions of the plate by screws 70 and provided with alined slots through which the slide 60 moves.

At its front end the slide 60 is provided with a downwardly extending circular yoke or fork 12 which engages the annular slot 54 in the separable portion 52 and connects the slide to said portion so that axial movement of the separable portion may be caused by the slide without interfering with the rotation of said portion. The slide 60 has a bracket 74 secured by screws 76 to its upper side and this bracket is provided with an upstanding portion 78 in which is formed a vertical slot 80. The vertical slot 80 is engaged by a horizontal pin 82 extending outwardly from a lever 84 pivoted on a stud screw 86 (Fig. 2) threaded into an upstanding portion 88 of another bracket 90 secured by screws 92 to a portion of the supporting plate 62 located inwardly of the slide 60. The lever 84 has a handle 94 by which it may be swung about its pivot 86 from the forward position shown in Fig. 1, to the rearward position shown in Fig. 2. A pair of pins 96, 98 mounted in the lever 84 and projecting inwardly therefrom serve as stops for the lever by their engagement with the bracket 90 and thus determine, respectively, the forward and rearward positions of the lever. Swinging movement of the lever 84 into the positions shown in Figs. 1 and 2 moves the slide 60 forwardly and rearwardly through the engagement of the pin 82 with the vertical slot in the bracket 78. By this arrangement, the separable portion 52 of the co-operating roll may be moved axially away from and back against the fixed portion 50 at the will of the operator as, for example, when the rolls are about to operate upon the heel portion of the upper or when they have finished operating upon said heel portion.

The cooperating roll 48 is also arranged to be moved or swung yieldingly into and out of operative relation with the supporting roll 24 to permit the upper to be mounted on the roll 24 or removed therefrom, the rolls normally being separated from each other heightwise of the machine. The pivoted bracket 34 is normally maintained in an upwardly inclined position forwardly of the machine by a compression spring 100 surrounding a treadle rod 102 extending upwardly through openings in the base 10 and the bracket 34, the lower end of the spring engaging the base and its upper end engaging a collar 104 secured to the treadle rod by a set screw. The treadle rod extends above the bracket 34 and is surrounded at its upper portion by another compression spring 106 which, as herein illustrated, is somewhat stronger than the spring 100, the lower end of the spring 106 engaging the plate 62 on the bracket and its other end engaging a nut 108 threaded on the upper end of the treadle rod, the nut 108 providing means for adjusting the tension of the spring. The spring 106 normally holds the bracket 34 against the fixed collar 104 on the treadle rod. When the treadle rod is depressed against the action of the spring 100, the bracket 34 swings downwardly about its pivot 32

and moves the roll 48 into operative engagement with supporting roll 24, the spring 106 being thereafter compressed by continued depression of the treadle rod. The spring 106, therefore, permits the rolls to be moved together yieldingly and, after they have come together, permits the pressure between them to be increased as desired as the spring continues to yield under further depression of the treadle rod, this depression being effected at this time against the action of both springs. Release of the treadle rod permits the spring 106 to expand and relieve the pressure between the rolls and permits the spring 100 to return the bracket and roll 48 to their upwardly inclined position.

In the operation of the machine briefly summarized, the prewelt shoe upper A (Fig. 3) is provided comprising a lining L and an outer layer O with the welt W attached to its lower edge by stitches S. The upper also has a counter stiffener C of fiber or similar material incorporated in its heel portion and preferably secured in place between the lining and outer layer by cement and also by the welt attaching stitches S. As herein illustrated, the upper A is a small sized upper for a high shoe or cack for children but it might obviously be an upper for a low shoe or, if desired, a large sized upper for men's or women's shoes. The upper is mounted on the supporting roll 24 preferably so that the roll initially engages it at one side thereof about opposite the heel breast line of the shoe and in such a position that the forward portion of the upper, from breast line to breast line, will be fed between the rolls before the heel portion is fed therebetween.

The treadle rod 102 is depressed to swing the bracket 34 downwardly to bring the roll 48 yieldingly against the upper and press it against the supporting roll 24, thereby conforming the upper to the shape of said roll and causing the thin edge portion 50 of the roll 48 to enter the space between the welt and upper and bend the welt over against the inclined surface 30 on the flange 28, the inner edges of the welt and upper being seated in the groove 26, as shown in Fig. 1. The power of the machine is started to rotate the rolls and cause them to feed the upper between them around its forward portion by friction. The rolls conform this forward portion to the shape of the supporting roll 24 and bend the welt downwardly simultaneously with the feeding operation, the position or angle into which the welt is bent relatively to the adjacent upper, as stated, being such that, after the operation is completed and the welt tends to react and return to its original position against the upper, the welt will return only part way to such position or into the substantially straight or flat position illustrated in Fig. 5.

After the forward portion of the upper has been conformed as described and the welt W has been straightened, the heel portion of the upper, containing the counter stiffener C, reaches the rolls. At this point, while the rolls continue to rotate and operate upon the upper, the lever 84 may be swung by its handle 94 from the forward position shown in Fig. 1 to the rearward position shown in Fig. 2, to move the separable portion 52 of the cooperating roll 48 axially along the reduced shaft 46 by forward movement of the slide 60. The separable portion 52 is thus moved at will away from the fixed portion 50 and out of position to engage the upper and conform it to the supporting roll 24, this axial

movement taking place while the separable portion 52 is rotating due to its connection to the fixed portion 50 by the rods 56.

Accordingly, as illustrated in Fig. 2, the heel portion of the prewelt upper will have its welt bent down and straightened as desired but the portion of the upper above or to the left of the portion 50 of the roll will not be engaged by the separable portion 52 and therefore will not be affected thereby. When the entire upper has been fed between the rolls so that its lower portion has been shaped and the welt has been straightened around the entire upper, the treadle rod is released to permit the spring 100 to elevate the roll 48 so that the upper may be removed from the supporting roll after which it is ready for use in constructing the prewelt shoe in accordance with the further steps disclosed herein.

A sole is provided for use with the upper A, this sole comprising, as herein illustrated, a single laminated sole B made up of an inner layer I, preferably composed of leather or fiber, a leather outer or tread layer T, and a filler or midsole M composed of cork or other yieldable material. The three layers are cut to the desired shape and size, the inner layer I, as illustrated in Fig. 4, being a predetermined amount larger than the midsole M, and the outer layer T being larger than the inner layer I, so that, when the three layers are properly positioned one upon the other and are secured together by cement, such as latex or other cement, to produce the laminated sole B, the sole has a peripheral groove or channel G in its edge face equal in height to the thickness of the midsole and of sufficient depth widthwise of the sole to receive the inner marginal portions of the upper and welt, these portions having been turned inwardly by the conforming rolls substantially in position to enter the channel G, as shown in Fig. 5.

Before assembling the shoe parts, cement, preferably rubber cement, is applied to the outer or attaching face of the welt W, to the inner edges of the welt and upper, and to the inner side of the inturned portion of the upper. Cement is also applied to the channel G in the sole so that it covers the surfaces thereof including the relatively wide surface formed by the outer layer T.

In assembling the parts, the upper is preferably held as illustrated in Fig. 5 so that the welt is substantially flat. The sole B is held opposite the opening at the bottom of the upper. The sole is then bent or arched to shorten it lengthwise and, while thus bent, it is introduced into the opening in the upper until the inner surface of the outer layer T, which forms the outer surface of the channel G, engages the attaching face of the welt in which position the inner edges of the welt and upper are located substantially opposite or in line with the channel.

The sole is then released to permit it to spring back through resiliency to its original flat condition and thus cause it to assume its full length which, as shown in Fig. 6, causes the sole to engage the upper around its entire margin and to exert a tension or pull thereon which tends to draw the inner edges of the upper and welt into or partially into the channel G. Accordingly, upon the release of the sole B the sole and prewelt upper A become at once assembled in proper relation to each other while off a last with the upper fixed or "locked" against displacement with respect to the sole because the upper and

welt are now located in or partially in the channel completely around the sole.

The upper and welt are next tucked into the channel G for the full depth thereof either by hand or by a suitable tool 112, as illustrated in Fig. 7. After the upper and welt have been tucked fully into the channel G so that they engage the edge of the midsole M completely around the shoe, the cement applied to the channel, upper and welt is allowed to set to cause the sole to become cement attached to the prewelt shoe upper A.

While the cement securing the sole to the upper and welt will hold sufficiently during the construction of the shoe, it is not usually safe to rely upon cement alone to secure the sole permanently to the upper. The shoe may, therefore, be stitched in the same manner as a regular welt shoe by inserting outseam stitches H, these stitches, as shown in Fig. 8, being spaced outwardly from the upper and passing through only the welt and sole to attach the sole permanently to the welt and upper.

Since no last has been utilized to facilitate the assembling of the shoe parts or for shaping or conforming the upper to the shape desired in the finished shoe, and since the shape imparted to the upper by the rolls is not intended to be its final shape but is an initial or preliminary shaping operation the benefits of which will obviously be lost or altered during the subsequent operations of assembling, stitching, and so forth without a last in the shoe, it will be seen that after the sole B has been permanently attached by the stitches H, the upper, especially at its forward or toe portion, will usually be drawn into a relatively low or flat shape or position by the strains exerted in making the shoe, thus rendering this toe portion, as illustrated in Figs. 7 and 8, too low or flat to constitute a well shaped shoe.

The upper A is next shaped or conformed, particularly at its lower portion, to impart to it the shape desired in the finished shoe. As illustrated, this operation may be accomplished, for example, by utilizing an expandible member 114 (Fig. 9) such as an extensible form or last which is arranged to be inserted inside the shoe and to be expanded therein to engage the upper and give it the shape desired in the finished shoe.

The expandible last 114, as illustrated in Fig. 9, comprises a main or heel section 116, shaped in accordance with the shape desired in the heel portion of the shoe and having formed in its lower portion a horizontal slot extending lengthwise thereof. Fastened in this slot by pins 118 is an arm or tongue 120 which extends forwardly and is provided at its forward portion with horizontal slots 122 and 124. Arranged for sliding movement on this forward portion of the arm 120 are a middle or intermediate section 126 and a forward or toe section 128, these sections likewise being shaped in accordance with the shape desired in the finished shoe, the toe section 128, in particular, being curved and rounded to form a suitably shaped toe on the shoe. The two forward sections 126, 128 are provided with horizontal slots through or into which the arm 120 passes, the slot in the forward section 128 terminating short of its front end. The section 126 is slidably connected to the arm 120 by a pin 130 passing through the slot 122 and the toe section is similarly connected to the arm by a pin 132 passing through the slot 124, so that both forward sections can slide along the arm toward or

away from the heel section 116, their sliding movement being limited by the slots.

The two forward sections of the expandible last are caused to slide on the arm 120 by an eccentric comprising a horizontal disk 134 rotatably mounted in an opening in the heel section 116 by an upwardly extending shank 186 on the disk and by a pin 187 extending downwardly therefrom, the shank 186 having a square socket formed in its upper end arranged to be engaged by any suitable means, such as the tool 138, for rotating the disk. Projecting downwardly from the disk is an eccentric pin 140 which is connected to the middle section 126 by a link 142 pivotally engaging a pin 144 on said middle section. Another eccentric pin 146 mounted in the disk 134, farther off center than the pin 140, is connected to the forward section 128 by a link 148 positioned above the link 144 and pivotally secured to the forward section by a screw 150. Since the pin 146 is more eccentric than the pin 140, the forward section 128 will travel farther than the middle section 126 when the disk 134 is rotated to expand or contract the last, the arrangement preferably being such that the middle section moves about half the distance that the forward section moves so that the spaces between the several sections will remain substantially equal at all times.

To complete the construction of the prewelt shoe, the expandible last 114 is inserted in the shoe while contracted and it is then expanded lengthwise to cause it to engage the inner side of the upper and exert sufficient pressure thereon to conform the upper to the shape of the last, thereby imparting to the upper, particularly at its toe and heel portions, the shape desired in the finished shoe. The expandible last is permitted to remain in the shoe for a sufficient time to cause the upper to be conformed to the shape thereof, which may be from ten to twenty minutes. During this time, however, such finishing operations as may be necessary or desirable, such, for example, as edge trimming, setting, and so forth, may be performed to complete the construction of the prewelt shoe after which the last may be contracted and removed from the shoe.

The method of making prewelt shoes disclosed herein, including the final shaping of the upper by the expandible form or last, forms the subject matter of a copending application Serial No. 420,835, filed November 28, 1941, in my name as a division of the present application.

Having thus described my invention, what I claim as new and desire to secure by Letters Patent of the United States is:

1. In a machine for operating upon shoe uppers, a roll for supporting a shoe upper, and another roll pivotally movable toward and away from said supporting roll for cooperating therewith and for pressing the upper against the supporting roll to feed the upper between said rolls and simultaneously to conform it to the shape of said supporting roll, a portion of said cooperating roll being separable from another portion thereof to prevent said separable portion from operating upon the upper while said other portion continues to operate thereon.

2. In a machine for operating upon shoe uppers, a roll for supporting a shoe upper, and another roll cooperating with the supporting roll for pressing the upper against said supporting roll to feed the upper between said rolls and simultaneously to conform it to the shape

of the supporting roll, a portion of said cooperating roll being movable into a position away from another portion of the roll while the rolls are operating and being arranged to remain positively in such position during said operation to prevent said movable portion from pressing the upper against said supporting roll.

3. In a machine for operating upon shoe uppers, a roll for supporting a shoe upper adjacent to its lower margin, and another roll for pressing the upper against the supporting roll to feed the upper and to conform its lower portion to the shape of said supporting roll, said other roll being pivotally movable toward and from the supporting roll and having a portion thereof separable at will from another portion thereof to permit the removal of said separable portion from engagement with the upper while the rolls are operating upon said upper.

4. In a machine for operating upon shoe uppers, a roll for supporting a shoe upper having a counter stiffener in its heel portion, said roll corresponding in shape to that desired in the upper forwardly of said heel portion, and another roll movable radially toward and from the supporting roll for pressing the upper yieldingly against said roll to feed the upper and simultaneously to shape it to said supporting roll, a portion of said other roll being separable axially from another portion thereof while the rolls are operating to permit the removal of the separable portion from engagement with the upper when operating upon its heel portion, thereby preventing said separable portion from acting upon said heel portion or the counter stiffener therein.

5. In a machine for operating upon shoe uppers, a roll for supporting a shoe upper, another roll cooperating therewith for pressing the upper against the supporting roll to feed the upper between the rolls and simultaneously to conform it to the shape of said supporting roll, said cooperating roll having a portion thereof separable from another portion of said roll to prevent said separable portion from operating upon the upper, means for rotating said rolls, and means for moving said separable portion into a position away from the other portion of said cooperating roll and for holding it positively in such position while the rolls are rotating.

6. In a machine for operating upon shoe uppers, a roll arranged to extend inside a closed shoe upper off a last to support the upper from the inner side thereof, another roll cooperating with the supporting roll for engaging the upper and pressing it against the supporting roll to feed the upper and simultaneously to conform it to the shape of said supporting roll, said cooperating roll being complementary in shape to the supporting roll and having a portion normally engaging the rest of said roll but separable axially into a position remote therefrom while the rolls are operating, thereby permitting the removal of said separable portion from engagement with the upper when the rolls are operating upon some portions of the upper, and means for maintaining said separable portion positively in either of its two positions.

7. In a machine for operating upon shoe uppers, a roll for supporting a prewelt shoe upper adjacent to the welt, said roll having means thereon for determining the position of the welt relatively to the adjacent upper, a roll cooperating yieldingly with the supporting roll for forcing the welt yieldingly against the welt

positioning means and for pressing the adjacent upper yieldingly against the supporting roll to conform it to the shape thereof, a portion of said cooperating roll being separable at will into a position remote from the rest of said roll while the rolls are operating without interfering with the operation on the welt to prevent the separable portion from conforming some portions of the upper to the shape of said supporting roll, and means for holding the separable portion positively in said remote position.

8. In a machine for operating upon shoe uppers, a roll arranged to extend inside a prewelt shoe upper off a last to support the upper from its inner side adjacent to the welt, said supporting roll having a surface thereon for determining the position of the welt relatively to the adjacent upper, another roll cooperating with the supporting roll and arranged for swinging movement relatively thereto, said cooperating roll being provided with a portion complementary to the supporting roll for entering between the welt and adjacent upper and forcing the welt against said surface to position said welt and for also pressing said upper against the supporting roll to feed the upper and simultaneously to conform it to the shape of said supporting roll, said cooperating roll having another portion thereof separable at will from said complementary portion while the rolls are operating to permit removal of said separable portion from engagement with the upper when the rolls are operating upon the heel portion thereof, thereby preventing the rolls from conforming said heel portion to the shape of said supporting roll, and means for swinging said cooperating roll into operative relation with said supporting roll.

9. In a machine for operating upon prewelt shoe uppers off lasts, a roll arranged to extend inside a prewelt shoe upper off a last and having a counter stiffener in its heel portion, said roll being arranged to support the upper from its inner side adjacent to the welt and being shaped in accordance with the shape desired forwardly of the heel portion of the upper, said roll having an inclined surface thereon adapted to position the welt at a predetermined angle relatively to the adjacent upper, another roll cooperating with the supporting roll and provided with a portion complementary thereto for entering the crease between the welt and upper and forcing the welt against said inclined surface to position the welt, said complementary portion being also arranged to press a lower portion of the upper against the supporting roll to feed the upper and simultaneously to conform said lower portion to the shape of the supporting roll, said cooperating roll having another portion thereof adjoining said complementary portion arranged to press a higher portion of the upper against the supporting roll to conform it thereto, said adjoining portion being movable at will axially toward and away from said complementary portion while the rolls are operating to permit said adjoining portion to be moved out of engagement with the upper without interfering with the operation upon the welt when the rolls are operating upon the heel portion of the upper, thereby preventing the rolls from acting upon said heel portion or the counter stiffener therein, and a slide for moving the adjoining portion of said cooperating roll toward or away from said complementary portion and for maintaining said adjoining portion positively in either position.

10. In a machine for operating upon shoe up-

pers, a roll for supporting a shoe upper off a last, said roll corresponding in shape to the shape desired in the upper forwardly of its heel portion, another roll cooperating with the supporting roll and movable radially toward and from the supporting roll for pressing the upper against said supporting roll to feed the upper and simultaneously to conform it to the shape of said supporting roll, said cooperating roll being complementary in shape to said supporting roll and having a portion thereof separable from another portion to prevent the separable portion from operating upon the upper, means for moving the cooperating roll radially into operative relation to the supporting roll, means for rotating said rolls to cause them to feed the upper and to operate thereon, and means for moving said separable portion away from the other portion of said cooperating roll when the rolls are operating upon the heel portion of the upper.

11. In a machine for operating upon shoe uppers, a roll for supporting a shoe upper off a last, a second roll for pressing the upper against the supporting roll to feed the upper and simultaneously to conform it to the shape of said supporting roll, a shaft for supporting said second roll, said second roll having a portion thereof separable axially along said shaft from the rest of said roll to prevent it from operating upon the upper, means for rotating said rolls, and means for moving said separable portion at will toward or away from the rest of said second roll while the rolls are rotating, said means including a slide, means for moving said slide, means connecting said slide to said separable portion, and means independent of said shaft for causing rotation of said separable portion during its axial movement.

12. In a machine for operating upon shoe uppers, a roll for supporting a shoe upper, a second roll cooperating with the supporting roll for pressing the upper against said supporting roll to feed the upper and to conform it to the shape of the supporting roll, shafts carrying said rolls, power operated means for rotating said shafts and rolls, said second roll having one portion thereof fixed to its shaft and another portion movable axially thereon and separable at will from the fixed portion to prevent it from operating upon the upper, means for moving said separable portion axially away from said fixed portion while the rolls are rotating, said means including a slide connected to said separable portion and a lever for moving said slide back and forth, and means carried by said fixed portion for causing rotation of said separable portion whenever it is adjacent to said fixed portion.

13. In a machine for operating upon shoe uppers, a roll for supporting a shoe upper off a last, said roll having a surface thereon for shaping the upper forwardly of its heel portion, a second roll for pressing the upper against the supporting roll to feed the upper and to conform it to the shape of said surface, said second roll having a portion separable from another portion thereof to prevent the separable portion from operating upon the upper, means for moving said rolls yieldingly toward each other, means for rotating the rolls, and means for moving the separable portion of said second roll axially away from its other portion while the rolls are rotating, thereby permitting the rolls to operate around the heel portion of the upper without conforming said heel portion to the shape of said rolls, said means including a slide connected to

said separable portion and arranged for movement back and forth in a plane parallel to the axis of said separable portion, a pivoted lever for moving said slide, and a plurality of rods fixed to said other portion and slidably engaging said separable portion for causing said separable portion to rotate while permitting axial movement thereof toward and away from said other portion during the rotation of the rolls.

14. In a machine for operating upon shoe uppers, a roll for supporting a shoe upper off a last from the inner side of said upper, said roll having a surface thereon for shaping the upper forwardly of its heel portion, a second roll for pressing the upper against the supporting roll to feed the upper and simultaneously to conform it to the shape of said supporting roll, shafts for supporting said rolls, means for rotating said shafts, said second roll having a portion thereof fixed to its shaft and another portion separable from the fixed portion to prevent the separable portion from engaging the upper and conforming it when the rolls are operating upon its heel portion, said separable portion having an annular groove therein, a slide movable back and forth in a plane parallel to the axis of said second roll, means on the slide for engaging the groove in said separable portion, and a pivoted lever for moving said slide back and forth and thereby

moving said separable portion axially toward and away from the fixed portion of said second roll.

15. In a machine for operating upon shoe uppers, a roll for supporting a prewelt shoe upper off a last adjacent to the welt thereon, said roll being shaped in accordance with the shape desired in the upper forwardly of its heel portion and having a flange thereon for positioning the welt at a predetermined angle to the adjacent upper, a second roll cooperating with the supporting roll for pressing the upper against it to feed the upper and simultaneously to conform the upper to the shape of said supporting roll and for also forcing the welt against said flange to position said welt at the desired angle, means for rotating said rolls, said second roll having a portion thereof separable at will from another portion while the roll are rotating to prevent the separable portion from acting upon the upper, and means for moving said separable portion axially away from the other portion of said second roll, said means including a slide connected to said separable portion, a lever for moving said slide, and means slidably engaging said separable portion for causing rotation of said separable portion when it is in engagement with said other portion.

ADRIEN L. JALBERT.
